AIRCRAFT ANTENNA MAST FOR SUPPORTING INTERMEDIATE PORTION OF ANTENNA WIRE

William C. Rogers, 5365 NW. 36th St.,
Miami Springs, Fla. 33166

Filed Jan. 19, 1968, Ser. No. 10,222

Term of patent 14 years

(Cl. D26—14)

FIG. 3

FIG. 4

FIG. 8

FIGURE 1 is a perspective view of an aircraft antenna mast designed in accordance with a preferred embodiment;

FIGURE 2 is a side of one view of the antenna mast shown in FIGURE 1 illustrating a side opposite to that shown in FIGURE 1;

FIGURE 3 is an end elevational view of the FIGURE 1 antenna mast, viewing FIGURE 2 from the right, it being understood that this view is substantially equally applicable to either end of the FIGURE 1 mast;

FIGURE 4 is a top plan view of the FIGURE 1 antenna mast;

FIGURES 5, 6 and 7 are cross sections of the FIGURE 1 antenna mast as viewed along the section lines 5—5, 6—6 and 7—7 of FIGURE 2;

FIGURE 8 illustrates a modified form of the FIGURE 1 design embodiment wherein the mast extends substantially vertical with respect to its base, it being understood that mast cross sections and all other mast details remain

substantially identical with corresponding design aspects of the preferred embodiment shown in FIGURES 1 through 7.

The dominant features of my design reside in the portions shown in full lines.

I claim:

The ornamental design for an aircraft antenna mast for supporting intermediate portion of antenna wire, substantially as shown and described.
